(57) **CLAIM**

We claim the ornamental design for a fabric cutter, as shown and described.

DESCRIPTION

FIG. 1 is an isometric view of a fabric cutter;
FIG. 2 is a top plan view thereof;
FIG. 3 is a bottom plan view thereof;
FIG. 4 is a right side elevational view thereof;
FIG. 5 is a left side elevational view thereof;
FIG. 6 is a front elevational view thereof;
FIG. 7 is a rear elevational view thereof;
FIG. 8 is an isometric view of another embodiment of the claimed design;
FIG. 9 is a top plan view of the embodiment shown in FIG. 8;
FIG. 10 is a bottom plan view of the embodiment shown in FIG. 8;
FIG. 11 is a right side elevational view of the embodiment shown in FIG. 8;
FIG. 12 is a left side elevational view of the embodiment shown in FIG. 8;
FIG. 13 is a front elevational view of the embodiment shown in FIG. 8; and,
FIG. 14 is a rear elevational view of the embodiment shown in FIG. 8.
The broken lines in the drawings are for illustrative purposes only and show unclaimed aspects of the claimed design.
